2 SHEETS-SHEET 2.

UNITED STATES PATENT OFFICE.

MARK J. GRETSCH, OF NEW YORK, N. Y., ASSIGNEE, BY DIRECT AND MESNE ASSIGNMENTS, OF ONE-HALF TO VERA GRETSCH AND ONE-HALF TO ISIDORE LEVITON, BOTH OF NEW YORK, N. Y.

PULL-SOCKET.

1,294,794.

Specification of Letters Patent. Patented Feb. 18, 1919.

Application filed May 12, 1917. Serial No. 168,103.

To all whom it may concern:

Be it known that I, MARK J. GRETSCH, a citizen of the United States, and a resident of the borough of Manhattan, city and State of New York, have invented certain new and useful Improvements in Pull-Sockets, of which the following is a description in such full, clear, and exact terms as will enable any person skilled in the art to which it pertains to make and use the same.

My invention relates to an improvement in electric pull sockets *i. e.*, the sockets for incandescent lights or bulbs in which the circuit to and from the light is controlled by a mechanism operated by a pendant chain, one pull on which closes the circuit and lights the lamp and another pull on which will break the circuit and extinguish the light.

The object of the invention is to reduce these devices to the simplest possible form and allow their construction at a low cost. Such devices are necessarily complicated and have been proposed in innumerable forms. My invention is the result of prolonged study of the problem of constructing the parts so that they will be strong and certain of action and at the same time reducing the number of parts and simplifying their forms so that I can place upon the market a perfectly serviceable device at a lower cost than that heretofore offered.

It is further an object of the invention to produce all of the elements in an extremely strong and durable form so that they will operate satisfactorily and stand up under continuous usage.

With these and other objects in view the invention resides in the improvements in the construction of the parts of the device and in their combination with each other which will be fully set forth hereinafter and particularly pointed out in the claims.

Reference is had to the accompanying drawings which represent as an example the preferred embodiment of my invention.

In these drawings—

Figure 1 is a side view of the lamp socket with a part broken away.

Fig. 2 is a sectional elevation on the line 2—2 of Fig. 1, but the main portions of the porcelains or insulators and the parts contained therein being left in elevation.

Fig. 3 is a plan view of the device with the metal shell removed, showing the chain trumpet in place.

Fig. 4 is a bottom plan view of the same parts, the sheet metal shell or casing being removed but the chain trumpet appearing as well as the threaded sleeve which receives the incandescent light bulb.

Fig. 5 is a section on the line 5—5 of Fig. 3.

Fig. 6 is a sectional elevation on the line 6—6 of Fig. 5.

Fig. 7 is a detail section on the line 7—7 of Fig. 4 particularly showing the connection to the center contact of the bulb.

Fig. 8 is a cross-section on the line 8—8 of Fig. 4.

Fig. 9 is an enlarged bottom plan view of the top porcelain section showing the commutator, pull chain arm, arbor and the appurtenant parts in position.

Fig. 10 is a top plan view of the bottom section of the porcelain.

Fig. 11 is a detail perspective of the bearing stud for the arbor which stud is attached to the upper porcelain section.

Fig. 12 is an enlarged end view of the arbor.

Fig. 13 is a side view of the arbor.

Fig. 14 is an elevational view of the pull chain arm showing the ratchet plate thereon.

Fig. 15 is an end view of the pull chain arm.

Fig. 16 is a section on the line 16—16 of Fig. 14.

Fig. 17 is a side view of the commutator or contact ratchet.

Fig. 18 is an edge view thereof.

Fig. 19 is an opposite side view of the same.

Fig. 20 is a section on the line 20—20 of Fig. 17.

Figs. 21 and 22 are detail elevations of the locking devices of the lower shell section, and

Fig. 23 is a bottom plan of the upper shell section showing the complementary locking devices.

My improved pull socket is incased in a brass or other shell formed of a cylindric body or lower part 25 and a cap of upper part 26. These parts 25 and 26 are separately connected as shown in Figs. 1, 2, 21, 22

and 23, from which it will be seen that the section 25 has a bead 25^a near its top edge and below it slots 25^b. From one of the slots 25^b a downward extension 25^c projects to receive the chain trumpet as will herein-after appear. The top shell section 26 has a rounded lower edge 26^b (see Figs. 1 and 23) which snaps over the bead 25^a and then by turning the parts of the shell the tongues 26^a will snap into the slots 25^b and securely yet removably lock the parts together. The shell is provided with an insulation lining in sections 30 and 30^c, the lower section adapted to the body 25 and the upper section adapted to the dome or upper section 26 as shown in Fig. 2.

The operating mechanism of the pull socket is, according to previous practice, supported in and by two sections of insulation material which are preferably molded of porcelain and are designated 31 and 32 in the drawings, 31 being the upper section and 32 the lower. These porcelain sections are shaped to receive and mount the various elements as will appear from the following description and they are held together preferably by two bolts 33 and 34 which pass vertically through the sections and serve also to hold the roll threaded sleeve 35 in which the incandescent electric lamp is screwed.

The electric lamp as is well known, has a contact at the side and a contact at the center. The side contact which is usually a roll threaded sleeve screws into and makes contact with the sleeve socket 35 and the center contact of the lamp is adapted to engage a yielding metal arm 36 with which it makes contact thereby completing the circuit to the lamp.

The center contact 36 as best shown in Fig. 7 is formed of a strip of metal suitably bent and passes through an opening 32^a in the lower porcelain section 32 and thence up into a side recess 31^a in the porcelain section 30, the shank of this contact 36 having a bend 36^a therein which lies between the porcelain sections 31 and 32 and is thereby held in place. The upper part of the shank, it will be noted from Fig. 7, also fits snugly in the recess 31^a in the porcelain section 31 and is at its upper portion provided with a screw 37 to which the leading-in wire 29 is adapted to be connected, this wire passing downward from the top of the upper section 31 of the porcelain through an extension of the side recess 31^a therein so that it does not interfere with the housing or roll which incloses the working parts and which is composed of the sheet metal sections 25 and 26 and the lining sleeve 30 before described.

It will be noted therefore that the circuit from the central contact of the incandescent light is completed through the yielding fin-

ger 36 and its shank as shown in Fig. 7 and thence through the screw 37 to the connecting wire 29.

The other branch 29^c of the circuit passes in (see Fig. 5) to a screw 38 in a bracket 70 arm 39 which is shown in detail in Fig. 11. In Fig. 11 the orifice for the screw 38 is indicated at 38^a but the screw is not shown. The bracket arm 39 has its upper end 39^a bent laterally and said bracket arm is placed in a cavity 31^b in the upper porcelain 31, it bent end 31^a being engaged with a screw 40 in the upper porcelain 31 whereby said bracket arm is held in place. The wire 29^c passes transversely from the bracket arm 39 as shown best in Fig. 2 and through the groove 31^c to the upper part of the porcelain, the lower extremity of this groove 31^c being also indicated in Fig. 5.

The lower end of the bracket arm 39 terminates at about the lower edge of the porcelain section 31 in a recess 39^b in which is rotatably mounted one end of the transverse arbor 41 and to which arbor the current is communicated through the bracket arm 39 and the connections before described. 42 indicates a spiral spring which is coiled around the arbor 41 and serves to actuate the commutator devices in a fashion which will be hereinafter fully set forth, but one end of said coil spring 42 is anchored under a finger 39^c at the lower end of the bracket arm 39 and at one side of the before described bearing 39^b for the arbor 41. The arbor 41 is shown in detail in Fig. 13 and Fig. 9 shows an enlarged bottom end view of the upper porcelain 31 and the lower end of the bracket arm 39. Fig. 9 also shows the finger 39^c with the end of the spring 42 thereunder as described.

The arbor 41 is mounted in a peculiar manner as will appear best from Figs. 5 and 9. The arbor has a squared portion 41^a and a reduced round portion 41^b at the end opposite the end which is seated in the bearing 39^b of the bracket arm 39. This reduced end 41^b is placed vertically and the whole arbor in fact, is allowed a vertical wobbling motion in a slot 31^d in the top porcelain section 31 (see Fig. 5). But a spring 43 is placed in the top porcelain 31 in a suitable cavity and bears down on the end 41^b of the arbor 41 so that the same is yieldingly held in position shown in Fig. 5 in which the end 41^b of the arbor 41 bears on the top edge of the lower porcelain section 32.

Mounted to turn loosely on the arbor 41 adjacent to the squared portion 41^a thereof, is a crank arm 44 of insulation material (preferably indurated fiber). This crank arm plays freely back and forth on the arbor but is held yieldingly in the position shown in Figs. 6 and 8 by the before described spring 42 the end of which opposite

the bracket arm 39, is bent laterally and engaged with the crank arm 44 so that the arm is thus held as shown in Fig. 6 and when thrown by the pull chain 45 is, upon the release of said chain, returned to the position shown in Fig. 6 by the spring 42. The pull chain 45 is the characteristic chain of these devices and passes outside of the socket so as to hang pendant therefrom through a trumpet 46. This trumpet has a base plate 47 to which it is attached and the same is seated in a cavity 31^c in the side of the upper porcelain section 31, the same being an extension of the cavities in the porcelain section 32 provided for the reception of the crank arm 44 and commutator to be hereinafter described. When the sheet metal sections 25 and 26 are engaged and locked by their bayonet joint connections above mentioned, said sections lie over the base plate 47 and hold the base plate and trumpet securely in position. The base plate lies flat against the upper porcelain section 31 but has at its upper and lower edges indent portions which enter the aforesaid cavity 31^c, the lower indent portion lying on top of the porcelain section 32 and the upper indent part of the base plate lying against the top wall of the above mentioned recess 31^c in said porcelain section 31. The trumpet 46 projects through the opening 25^c in the shell section 25. The pull chain 45 as best shown in Figs. 14 and 15 is engaged with the crank arm 44 by means of a recess in the crank in which one of the ball links of the pull chain 45 is seated. A downward pull on the chain 45 therefore throws the arm from the horizontal position shown in Figs. 6 and 9 upward to a substantially vertical position which throw is transmitted in a rotary motion to the arbor 41, through the ratchet device hereinafter described, and is sufficient to either make or break the circuit of the lamp and when the pressure on the chain 45 is relaxed the spring 42 throws the crank arm back to its position of rest which is that indicated in Figs. 6 and 8.

As best shown in Figs. 14, 15 and 16 the crank arm 44 has the ratchet device fastened thereto which is formed of a metal plate 48 having four ratchet teeth 48^a struck up therefrom and which plate is laid sidewise on the crank arm 44 and fastened thereto preferably by a boss 48^b which enters the central opening in the arm 44 and also by lapping the edges 48^c of the plate 48 around the hub portion of the crank arm. The ratchet teeth 48^a are adapted to coöperate with a commutator or make and break contact device which is carried fast on the squared portion 41^a of the arbor 41.

The commutator or make and break contact device is shown in detail in Figs. 17

to 20 and it comprises a body 49 of fiber or other approved insulation material with a squared central orifice 49^a to receive the squared portion 41^a of the arbor 41. This insulation body 49 is sheathed with a metal 70 covering 50 on one side thereof which is extended to form teeth 50^b on two opposite of the four teeth 49^c of the commutator so that the commutator, having four teeth 49^c, has two of said teeth shod with the metal 75 50^b and two of the teeth unshod, the first pair of teeth transmitting the current and the second pair of teeth being uncovered insulation therefore not transmitting the current. The metal covering 50 of the commutator has indentations 50^c next to its teeth 50^b there being two of such indentations respectively corresponding to the two teeth so that the commutator device lying as it does, along side of the crank arm 44, with its 80 attachments matched together to form a ratchet movement according to the operation of which the back and forth movement of the arm 44 imparts to the commutator device a step by step forward rotation. 85

Now referring to Fig. 8 it will be noted that the teeth of the ratchet 49 in the course of rotation thereof are adapted to project successively into an opening 32^b made in the bottom of the insulating section 32 and in coöperation with the right hand end wall of said opening, which forms an abutment will prevent a retrograde movement of the ratchet, so that as the back and forth movement of the crank arm 44 imparts a progressive step 100 to it. The engagement of the teeth with the 105 said abutment is rendered possible by reason of the wabbling lateral support of the arbor 41. As the ratchet is rotated in clockwise direction the cam shaped surfaces of the teeth thereof in sliding over the bottom 110 of the section 32 will first raise the arbor 41 against the tension of the spring 43 and on the tooth entering the opening 32^b the arbor 41 will be pressed downwardly by the said spring causing the tooth to engage the right 115 hand end wall of said opening which as stated will form an abutment and prevent the retrograde movement of the ratchet.

It will be seen that current is transmitted from the arbor 41 to the ratchet plate 48 of 120 the crank arm 44 and thence to the sheathing 50 of the commutator 49 and thence to a contact finger 51 which extends through an opening 32^c in the insulation section 32 and is part of a metal plate 51^a which is 125 fastened to the under side of the insulation section 32 by the bolt 34. But it should be noted that this plate 51^a engages the bottom surface of a flange 35^b formed on the screw socket 35 so that it makes electrical contact 130

therewith and carries the current to the threaded side shell of the incandescent light. The incandescent light therefore is screwed into the metal socket 35 and makes contact therewith on one point of its circuit while the other point makes contact with the center contact 36 before described thus completing the circuit in the lamp. The circuit to the lamp passes from the wire 29^a to the bracket arm 39, thence to the arbor 41 and from it to the sheathing 50 and from the sheathing to the tongue 51 and thence to the threaded socket 35 returning from the central contact of the electric lamp to the tongue 36 and thence out to the wire 29 through the connections shown in Fig. 7 and above described.

In summary, therefore, it will be seen that upon a downward pull on the pendant chain 20 45 the crank arm 44 is thrown over from the horizontal position shown in Fig. 8 to a vertical position, and that the ratchet teeth 48^a and corresponding formation 50^a of the sheathing 50 of the commutator 49 will result in a one-quarter revolution of the commutator and the return of the arm 44 to the horizontal position shown in Fig. 8. Repeated movements of this kind will result in a continued step by step progressive 30 35 rotation of the commutator and in an alternate engagement and disengagement of the sheathing of the commutator with and from the finger 51 thus carrying the current to the socket 35 and igniting or extinguishing the lamp as the case may be.

While the invention here shown is especially designed in all of its principles to what are known as pull sockets, *i. e.* those sockets operated by a chain, nevertheless 40 45 certain features are necessarily useful in connection with what are known as key sockets and indeed any form of lamp socket and it should be understood that the patent is not necessarily limited to any particular type of socket.

What I claim is:—

1. A lamp socket having an insulation section formed with a recess and a ratchet shaped commutator rotatably supported in said socket and adapted to at times enter with a tooth into said recess and engage the wall thereof which lies in its path so as to become locked therein against retrograde movement.
5. 2. A lamp socket having an insulation section formed in its bottom with a recess, a ratchet shaped commutator revolving in said socket and capable of yielding at a right angle to the bottom of said section and to enter with a tooth into said recess so as to be locked against retrograde movement.
10. 3. A lamp socket having an insulation section formed with a recess in its bottom, a laterally wobbling arbor in said socket, a ratchet shaped commutator on said arbor,

the teeth of which are adapted to successively enter the said recess so as to lock said commutator against retrograde movement.

4. A lamp socket having a sectional insulation body of which one section has a recess, 70 an arbor mounted to rotate therein, a crank arm turning loosely on the arbor, a ratchet part on the crank arm, a commutator fastened to the arbor and having a ratchet part coacting with the ratchet part on the crank 75 arm, the teeth of said commutator being adapted to successively enter said recess to prevent retrograde movement of the commutator and means on the commutator for making and breaking the lamp circuit. 80

5. A lamp socket having an insulation frame part with a recess therein, a conducting cylindrical part to receive the lamp and to take the current to the side thereof, an arbor mounted in the frame part, means for 85 leading the current to the arbor, contact devices coacting with the arbor to make and break the connection with said cylindrical part and having teeth adapted at times to enter said recess to prevent retrograde movement of said contact device and means for returning the circuit from the central contact of the lamp. 90

6. A lamp socket having a toothed make and break commutator device, manually 95 operated means for operating the same, a circuit completing device to carry the current from the commutator device to the side of the lamp, a constantly connected conducting device for taking the current from the 100 central contact thereof and stationary means to at times engage the teeth of the said commutator devices to prevent retrograde movement thereof.

7. A lamp socket having an insulation 105 frame work having a recess, a bracket arm thereon to carry the current, an arbor having a bearing in the bracket arm and also receiving the current therefrom and toothed make and break devices for controlling the movement of the current from the arbor to the lamp and adapted during rotation to snap with a tooth into said recess to prevent retrograde movement. 110

8. A lamp socket having an insulation 115 frame work having a recess, a bracket arm therein adapted to carry the current, an arbor having one end mounted in the bearing in the bracket arm and receiving the current therefrom, the other end of the arbor being 120 laterally movable, a spring pressing the other end of said arbor laterally and ratchet shaped make and break contact device mounted on the arbor and adapted at times to enter with a tooth said recess to prevent 125 retrograde movement.

9. A lamp socket having an insulation frame work having a recess, a bracket arm 130 therein adapted to carry the current, an arbor having one end mounted in the bear-

ing in the bracket arm and receiving the current therefrom, the other end of the arbor being laterally movable, a spring pressing the other end of said arbor laterally and 5 ratchet shaped make and break contact devices mounted on the arbor and adapted at times to enter with a tooth said recess to prevent retrograde movement, and a torsional spring on the arbor one end of which is 10 anchored to the bracket arm.

10. A lamp socket having an insulation frame work having a recess, a conducting cylinder to receive the lamp, a fastening extending through the frame work and engaging the cylinder, a contact finger to engage the central contact of the lamp, means mounting the contact finger on the insulation frame work and for taking the current to or from said finger, a second contact finger 15 in connection with the said conducting cylinder, the second contact finger projecting into the interior of the frame work and a toothed make and break ratchet mechanism in said frame work coating with said 20 contact finger and adapted at times to enter with a tooth said recess to prevent retrograde movement of said mechanism.

11. A lamp socket having an insulation

frame work, conducting cylinder to receive the lamp, a fastening extending through the frame work and engaging the cylinder, a contact finger to engage the central contact of the lamp, means mounting the contact finger on the insulation frame work and for taking the current to or from said finger, a 30 second contact finger in connection with the said conducting cylinder, the second contact finger projecting into the interior of the frame work and a make and break ratchet mechanism in said frame work coating with 35 said contact finger, said make and break contact mechanism comprising a wabbling arbor and a ratchet commutator mechanism thereon, the ratchet commutator mechanism co-acting with a stationary abutment on the 40 frame work whereby the rotation of the ratchet brings about a laterally wabbling of the arbor.

In testimony whereof I have hereunto signed my name in the presence of two witnesses.

MARK J. GRETSCH.
